INVENTOR:

Solomon Wise
BY Allen Allen

ATTORNEYS.

UNITED STATES PATENT OFFICE.

SOLOMON WISE, OF CINCINNATI, OHIO.

LOCK.

1,390,222.

Specification of Letters Patent. Patented Sept. 6, 1921.

Application filed May 6, 1920. Serial No. 379,386.

To all whom it may concern:

Be it known that I, SOLOMON WISE, a citizen of the United States, and a resident of the city of Cincinnati, in the county of Hamilton and State of Ohio, have invented certain new and useful Improvements in Locks, of which the following is a full, clear, and exact description, reference being had to the accompanying drawings, forming a part of this specification.

My invention relates to key operated locks, having tumblers, and more particularly to that type of locks wherein one set of tumblers is brought into line by another set, or by a suitable key, thereby forming a line of cleavage for the opening of the locked members that carry said tumblers.

It has as its object the provision of a lock which is operated by a double set of concentric plungers and by such means to provide a lock of great strength and safety and at the same time, one which is simple to manufacture and assemble, and hence quite inexpensive.

My objects and other advantages to be noted I accomplish by that certain construction and arrangement of parts to be herein-after more specifically pointed out and claimed.

In the drawings,

Figure 1 is a sectional view taken centrally through a padlock illustrating my invention and showing the lock closed.

Fig. 2 is a like view of Fig. 1 showing the lock after it has been released.

Fig. 3 is a perspective view of the various springs as employed in connection with the lock shown in Figs. 1 and 2.

Fig. 4 is a side elevation of the key for the lock in Figs. 1 and 2.

Fig. 5 is an edgewise elevation of another form of lock.

Fig. 6 is a cross section of the said other form of lock, showing same in closed position.

Fig. 7 is a like view to Fig. 5 showing the lock released.

The two locks shown in the drawings have been selected by me as simple means of illustrating the principle involved in my invention, and not at all as indicating any limitations in the application of my invention to locks in general.

The lock shown in Figs. 1 and 2 comprises a body portion 1 having a cylindrical opening 2 for the operating plungers or tubes, and a socket 3 for the shackle, this lock being a padlock. The cylindrical opening opens inwardly of the body, toward an opening 4 in which slides the block 5. The block 5 carries the swiveled shackle 6, which when the block is in locked position will be engaged in the socket 3, and when the block is moved along in the opening 4, will be free of the socket, so as to permit removal of the padlock from whatever device is in engagement therewith.

There will be a casing around the lock, as at 7, inclosing the slideway for the block, and the cylindrical hole in the lock body will terminate outwardly in a slot 8, through which the key will be inserted. The block has a cylindrical passage-way 9 therein for a series of tubular plungers, as in the case of the body, the parts being so arranged that the tubular plungers in the block will be projected into the cylindrical bore in the body, when the padlock is closed.

The tubular concentric plungers which form the basis of my invention, independent of the form of mechanism in which they are used, are shown in both illustrations as being four in number. Thus the locking plungers are shown at 10, 11, 12 and 13, said plungers being mounted one inside of the other so as to form, preferably, a snug sliding fit. The inner plunger need not be tubular, as it forms the core of the plunger assembly.

With each set of locking plungers, there are furnished a set of springs, likewise concentric, as shown at 10^a, 11^a, 12^a and 13^a, running from a wide to a narrow diameter.

As is evident the absolute fit into each other of the tubes or concentric plungers is not necessary, and the assembly of them into the lock is very simple. They are merely set together the one inside of the others and the springs likewise assembled. The springs are then dropped into the socket of the movable portion of the lock, and the plunger assembly dropped in after them.

The releasing or alining plungers are like the locking plungers concentrically mounted, and except for the inner one are of tubular form, as shown at 14, 15, 16 and 17, these

plungers fit snugly and slidably, although the exact dimension is not essential, and correspond in size to the locking plungers. They are easily assembled and are merely dropped 5 in place in the bore of the body of the lock.

The result of the structure now described is that when the block carrying the locking plungers is moved to a position which permits 10 its spring pressed plungers to move into the bore of the body of the lock, they will at once be projected therein, and prevent further movement of the block, until they each one move out of engagement with 15 the said bore.

To accomplish this unlocking movement, a key is provided having steps 14^a, 15^a, 16^a and 17^a, said steps being formed by preference at each side of the axis of the key, as 20 shown. There is also another stopping step 18^a to limit the inward motion of the key.

The key when inserted in the slot 8 will contact with the four plungers 14, 15, 16 and 17 and press them inwardly, and the 25 plungers of the two series are so proportioned as to length, that when the key has been pressed home in the slot, the releasing plungers will have depressed the locking plungers, so that they are all pressed out 30 from the bore of the body of the lock, and a line of cleavage formed between the two sets of plungers at the meeting line of the block and its slideway.

Nothing has been stated as to the definite 35 length of the plungers of the two series, since this may be as desired. I prefer, however, that they be of varying relative sizes, dependent upon the nature of the key that is to be employed.

40 As is evident the variety of locks may be extremely wide, when formed according to the concentric plunger principle which I have above described, since the length of each plunger may be varied fractional parts 45 of an inch, and each change of any plunger will vary the operation of the lock and require a different key. Thus in a lock of the character described having eight plungers in all, there may be a variation, within 50 quite wide limits of any one of the eight, which will demand a different shape of key and comprise a different lock which will open with no other key.

55 As another form of lock embodying a concentric plunger device, I have shown a revolving lock structure (Figs. 5, 6 and 7). In this structure the core 18 of the lock is held stationary in the casing 19, as is the plate 20, which in connection with 60 the casing forms the retaining socket for the locking bar.

The revolving piece 21 carries a locking bar or finger 22 and revolves around the central core, inside of the casing. The piece 65 21 has a cylindrical hole therein which car-

ries the unlocking plungers 14, 15, 16 and 17 and in a cylindrical hole 23, in the core are mounted the spring pressed plungers 10, 11, 12 and 13.

The casing has a slot 24 therein, which 70 is wide enough to permit the rocking of a key therein, said slot letting into the bore of the revolving piece. Thus the key may be inserted in the slot, and will bring the unlocking plungers and locking plungers 75 into line, and the cleavage point between the core and the revolving piece, whereupon the key is to be rocked, to swing the revolving piece and its finger 22 into unlocking position. 80

As heretofore stated, the above two embodiments of my invention are illustrative, and I do not desire that my claims that follow be limited in construction because of my failure to describe other structures likewise 85 illustrating the principle of my invention.

Having thus described my invention, what I claim as new and desire to secure by Letters Patent, is:—

1. In a padlock, the combination of a lock 90 body, having a recess in one face thereof, a block slidable but non-rotatable in said recess, a shackle carried by said block and extending through a wall of said recess, and means for inclosing said recess, secured to 95 the body, said block and body having sockets therein, spring-pressed concentric plungers arranged one within the other in the block socket, matching plungers in the body socket, and said body having an orifice for 100 insertion of a key to aline the meeting edges of the plungers to permit the block to slide.

2. In a padlock, the combination of a lock body, having a recess in one face thereof, a block slidable but non-rotatable in said recess, a shackle carried by said block and extending through a wall of said recess, and means for inclosing said recess, secured to 105 the body, said block and body having sockets therein, spring-pressed concentric plungers arranged one within the other in the block socket, matching plungers in the body socket, and said body having an orifice for 110 insertion of a key to aline the meeting edges of the plungers to permit the block to slide, 115 said sockets in the body and the block comprising holes extending through them, whereby the plungers may be assembled readily and the spring set in place in the block, and the plungers set into the body 120 through the recess therein prior to insertion of the block therein, in assembling the lock.

3. In a padlock, a lock body comprising a metallic body having a rectangular recess cut in one side thereof, so as to leave walls 125 at top and bottom of the recess integral with the body, a cover adapted to inclose the body and the recess, and be permanently secured thereon after assembly of the lock, a block to fit the recess, a shackle on the block 130

adapted to pass through the recess wall and engage the lock body at another point, holes in the block and the body adapted to register when the block is moved to bring the shackle to body-engaging position, and concentric plungers in the body and block, with springs to maintain them out of alignment at the meeting line of the block with the inner wall of the recess, said plungers being adapted to be alined at said point by means of a key inserted through the body from the opposite side thereof from the recess as and for the purpose described.

SOLOMON WISE.
